UNITED STATES PATENT OFFICE.

LEWIS P. LORD, OF MINNEAPOLIS, MINNESOTA, ASSIGNOR OF ONE-THIRD TO F. G. ACOMB, OF MINNEAPOLIS, MINNESOTA, AND ONE-THIRD TO W. H. KILLEEN, OF APPLETON, WISCONSIN

BERRY-BOX.

1,204,367.

Specification of Letters Patent. Patented Nov. 7, 1916.

Application filed November 13, 1915. Serial No. 61,298.

To all whom it may concern:

Be it known that I, LEWIS P. LORD, citizen of the United States, resident of Minneapolis, county of Hennepin, State of Minnesota, have invented certain new and useful Improvements in Berry-Boxes, of which the following is a specification.

My invention relates to berry boxes of the folding or collapsible type and the object of 10 the invention is to provide a box of simple, economical construction and one in which the fruit, when the boxes are piled one upon another, will be thoroughly ventilated.

Other objects of the invention will appear 15 from the following detailed description.

The invention consists generally in various constructions and combinations, all as hereinafter described and particularly pointed out in the claims.

20 In the accompanying drawings forming part of this specification, Figure 1 is a perspective view of a berry box embodying my invention, a portion of the wall being broken away to illustrate the manner of supporting 25 the bottom and the position of the ventilating holes therein, Fig. 2 is a plan view of the blank cut and scored, ready for folding, Fig. 3 is a perspective view through the box, showing the flange-like supports for the bottom panel.

In the drawing, the blank, Fig. 2, is shown composed of panels 2, 3, 4, and 5, formed by transverse score lines 6. The panel 5 has a flap 7 thereon for securing it to the opposite 35 end of the blank when it is folded to form the box. Each of the panels 3, 4 and 5 has a flap 8 formed thereon by a score line 9 running parallel with the opposite longitudinal edge of the blank and intersecting 40 the transverse score lines, these being cut through to allow the flaps 8 to be folded up into the box against the wall panels. The outer edges of these flaps have tongues 10 thereon which are turned inwardly when the 45 flaps are folded. At one end of the blank and extending at right angles thereto is a panel 11 which forms the bottom of the box, and the score line 9 is extended across this panel to form a folding line therefor, and 50 in addition a score line 12 is provided

parallel with the score line 9 and coinciding with the score lines between the tongues 10 and the flaps 8. The score lines 9 and 12 form a narrow panel 13 which is seated against the wall panel when the bottom is 55 folded up into the box. At the end of the panel 11 is a tongue 14.

On each side of the score line 9 and adjacent thereto I provide a series of openings 15, shown rectangular in form, though 60 the shape may be varied, if preferred. These openings, when the blank is folded, will be partially above the bottom of the box and partially below, as indicated in Fig. 1, and will admit a circulation of air not 65 only to the bottom of each box above the panel therein, but will also allow a circulation of air across the top of the box next beneath. Generally, in stacking fruit boxes, the space between the fruit and the bottom 70 of the box above is completely inclosed and there is no circulation of air whatever across the top of the fruit. With my improved box this objection is entirely eliminated and no matter how many boxes are piled upon one 75 another, the air may freely circulate over and under the fruit. I have also found that a panel cut and scored in this way can be easily and quickly folded and the bottom bent into position with comparatively little 80 effort or loss of time.

In various ways the details of construction herein shown and described may be modified and still be within the scope of my invention.

I claim as my invention:

1. A folding box comprising a blank of flexible material having parallel transverse score lines thereon at intervals to form a series of panels constituting the side walls 90 of the box, and the panel at one end of the box having a lateral extension to form the bottom thereof, said panel also having longitudinal parallel score lines intersecting said transverse score lines forming a group of 95 comparatively narrow flaps which are folded upwardly and inwardly when the box is set up and forming a support for the bottom panel, said flaps and said wall panels having openings therein which, when the box is 100

folded, are partially above and partially below the bottom panel, for the purpose specified.

2. A berry box composed of a blank of flexible material having wall and bottom panels, said wall panels having flanges depending below said bottom panel and adapted to rest upon the top of the box next beneath, said flanges having openings

therein to allow a circulation of air through 10 the space between the bottom panel of one box and the berries in the box next beneath.

In witness whereof, I have hereunto set my hand this 1st day of November, 1915.

LEWIS P. LORD.
